T. F. EUSTACE

WINDSHIELD GLASS RETAINING CLIP

Filed Jan. 18, 1924

UNITED STATES PATENT OFFICE.

THOMAS F. EUSTACE, OF CLEVELAND, OHIO.

WINDSHIELD-GLASS-RETAINING CLIP.

Application filed January 18, 1924. Serial No. 687,127.

To all whom it may concern:

Be it known that THOMAS F. EUSTACE, a citizen of the United States, residing at Cleveland, in the county of Cuyahoga and State of Ohio, has invented certain new and useful Improvements in Windshield-Glass-Retaining Clips, of which the following is a specification.

This invention is a windshield glass retaining clip and is designed for use as a substitute for the usual screws and such fasteners by which the glass is retained in its frame or sash.

An object is to provide a clip which will reliably retain the glass in place and at the same time be readily removable for replacement of glass.

It is likewise an object to provide a clip which may be readily attached and detached without resorting to the use of special or other tools.

Other objects will be in part obvious and in part pointed out hereinafter.

In order that the invention and its mode of operation may be readily understood by persons skilled in the art, I have in the accompanying illustrative drawings and in the following detailed description based thereon set out one possible embodiment of the same.

In these drawings:

Fig. 1. is a front elevation of a section of a sash showing my clips in dotted lines.

Fig. 2. is a detail showing the relative position of the glass and clip.

Fig. 3. is a horizontal section on the plane of line 3—3 of Figure 1.

Fig. 4. is a side elevation of the clip.

Fig. 5. is an end elevation of the clip, and

Fig. 6. is a view of the other end.

Ordinarily, the glass, particularly in windshields, is held in place by screws or similar fasteners, with the result that considerable time and labor is necessary in the assembly and additional time wasted where a broken glass is to be replaced by a new one. With the use of this clip these objections are overcome and a simple and inexpensive glass retainer is provided.

Having more particular reference to the drawings throughout which similar characters of reference designate similar parts, this windshield glass retaining clip may be broadly stated as comprising a block engageable with the lower edge of the glass and carrying a spring finger for engagement

with the sash or frame, whereby the glass is held against accidental displacement.

While the clip may be employed in a number of differently constructed sashes, I show, for illustration of the principle, a glass G mounted in a sash or frame F, this frame being formed of sheet metal folded to provide a pair of ways or channels W, one being U-shaped in cross section and receiving one edge of the glass. A packing 60 is arranged in the U-shaped channel to provide proper connection between the glass and its sash. As shown, there is no bottom bar on the sash and the lower ends of the end bars are open to permit of easy assembly and use of my clip. The lower end of 65 each end wall is cut away and provided upon its inner face with a block B which serves to limit the inward movement of the clip and to engage a spring finger whereby accidental removal of the clip is provided. The lower end of the dividing wall between 70 the channels is cut away and co-acts with the aforementioned block in limiting the inward movement of the clips.

Each clip consists of a block having a groove or channel to receive a portion of one edge of the glass and its packing strip and a spring finger to provide means for retaining the block in a predetermined relative position to the sash or frame of the windshield. Preferably, though not necessarily, this block is substantially L-shaped, the base portion 7 being channeled or grooved to form a pocket 8 in which a portion of the lower edge of a glass and its packing strips are arranged. The inner end of this pocket is vertically aligned with the inner face of the vertical portion of the clip. The lower outer edge of the clip is 95 enlarged to provide a shoulder or stop 9 which together with the inner upper edge of the base portion 7 serve to limit the inward movement of the clip through abutting the cut-away ends of the frame or sash. Adjacent the upper end of the clip a bevelled shoulder or boss 10 is formed and supports a flat spring finger 11, said finger being secured in place by means of a rivet 12 or other fastening element.

This bevelled shoulder directs the free end of the spring away from the vertical portion of the clip and creates a space or recess 13 in which the spring may move when this clip is being moved into engage-

ment with the glass and its frame or sash. The lower edge of the base portion of the clip is enlarged to provide a pair of oppositely directed ribs or flanges 14 which serve 5 as finger pieces for use in removing the clip and in addition serve to present a finished appearance to the wind shield as a whole.

An opening 15 is formed in the end wall of the frame or sash to permit of insertion 10 of a nail or the like for disengaging the spring finger and the shoulder.

The operation is simple, consisting of 15 positioning a glass in the frame, and sliding the clips into the frame until the fingers snap over the shoulders or stops. The means for removal was set out in the preceding paragraph.

Certain changes in the minor details of 20 construction may be resorted to and such changes as fall within the scope of the appended claims I consider my invention.

I claim:

1. A windshield glass retaining clip comprising a substantially L-shaped member, 25 one portion of said member being adapted for engagement with an edge of the glass, the other arm being engageable with the windshield frame and spring means for retaining said other arm and windshield 30 frame inter-engaged.

2. A windshield glass retaining clip comprising a substantially L-shaped member, one portion of said member being adapted 35 for engagement with an edge of the glass, the other arm being engageable with the windshield frame and retractable spring means for removably inter-connecting said other arm and the windshield frame.

3. A windshield glass retaining clip comprising a substantially L-shaped member,

one portion of said member being adapted for engagement with an edge of the glass, the other arm being engageable with the windshield frame, a spring finger carried by said other arm and adapted for engagement with the windshield frame.

4. The combination with a windshield including a hollow frame and a glass slideable thereinto through an open side; of a clip, a portion of the clip being slideable 50 into the frame, spring means for retaining said portion in the frame, and an arm included in the clip for engagement with one edge of the glass to retain the same in its frame.

5. The combination with a windshield including a hollow frame and a glass slideable thereinto through an open side; a substantially L-shaped clip, one arm of the clip being slideable into the frame, a spring finger carried by the arm and adapted to inter-connect the arm and frame, the other arm being engaged with one edge of the glass to retain the same in its frame.

6. The combination with a windshield including a hollow frame and a glass slideable thereinto through an open side; a substantially L-shaped clip, one arm of the clip being slideable into the frame, a spring finger carried by the arm and adapted to inter-connect the arm and frame, and a shoulder formed upon the frame to engage the spring finger, said frame having an opening to permit retraction of the spring finger, and the other arm being engaged with one edge of the glass to retain the same in its frame.

In testimony whereof, I affix my signature.

THOMAS F. EUSTACE.
